UNITED STATES PATENT OFFICE.

ERNEST R. VIBERG AND WALLACE C. PARKER, OF MONTREAL, QUEBEC, CANADA.

BOLSTER.

Application filed January 9, 1926. Serial No. 80,276.

This invention relates to new and useful improvements in bolsters for railway cars and particularly to the ends thereof and the object of the invention is to provide 5 a simple and inexpensive bolster, the ends of which will be so constructed that excessive wear of these ends due to frictional contact with adjacent portions of a truck will be practically eliminated.

10 Another object is to provide a bolster the ends of which will have a much better wearing and bearing surface than bolsters built in accordance with the methods at present in use.

15 Up to the present time, it has been difficult to construct a bolster end which would resist the wear due to frictional contact with portions of the truck body. Bolster ends as at present constructed have to be constantly 20 inspected for undue wear, and when this occurs, the bolster has to be dismantled for repairs, a very expensive item in the maintenance of rolling stock, resulting in putting the car out of commission for long 25 periods until such repairs are made.

In our invention we reduce the wearing of the ends to a minimum by making same or parts of same of metal having greater wearing qualities than malleable iron, cast 30 steel, mild steel or such like metals which are used in the construction of now standard types.

In the drawings which illustrate various forms of our invention:—

35 Figure 1 is a perspective view of one type of bolster which may be constructed according to our invention.

Figure 2 is a plan view of the device shown in Figure 1.

40 Figure 3 is an enlarged perspective view of a bolster end.

Figure 4 is a plan view of a bolster end of modified construction and with double guides on each side of each end.

45 Figure 5 is a side elevation of the device shown in Figure 4.

Figure 6 is a sectional end view taken on the line 6—6 Figure 4.

Figure 7 is a plan view of a bolster end 50 provided with one guide on each side of each end.

Figure 8 is a plan view of the bolster end shown in Figure 7.

55 Figure 9 is a partial end view of the bolster shown in Figure 7 looking in the direction of the arrow 9.

Figure 10 is a plan view of a bolster end in which the guides are formed in the side or rubbing plates.

Figure 11 is a side elevation of the device 60 shown in Figure 10.

Referring more particularly to the drawings, 21 designates the compression member of a bolster, 22 the tension member and 23 the central strut, all of which may be constructed of structural shapes and plates. Mounted on the upper side and in the centre of the compression member is the car body supporting bearing 24. Secured to the upwardly turned ends 25 of the compression 65 member are the saddles 26, which form a bearing surface for the side bearings 27 formed by bending the ends of the tension member around the ends of the compression member and securing them together by means of the rivets 28. Secured to the ends of the tension and compression members by any suitable means are the rubbing plates 29 which fit over the ends of the bolster members and may be riveted thereto by 70 means of the rivets 30 passing through the apertures 31 formed in the outer faces of the plates. In Figure 3 the rubbing plates are shown formed from one piece of metal bent in the form of a U, but the ends of 75 the bolsters may be modified as shown in Figures 4 to 10 inclusive. In Figures 4 to 9 inclusive, the ends are made in three sections, the two side sections being formed of plates 32 and the end section 33 of channel 80 formation adapted to overlap one edge of each of the plates 32 and riveted thereto by means of the rivets 34. In Figure 4 two guides or lugs 35 are riveted to each side plate while in Figure 7 only one guide or lug is riveted to each side plate. These 85 guides or lugs position the bolster in the car truck (not shown). In Figure 10 the lugs or guides 36 are made integral with the plates 32. Supporting channels or spacing 90 members 37 may be provided between the free ends of the plates and bolts 38 may be passed through these members and the tension and compression members to provide 95 a further means for securing the various members of the bolster together.

The above construction is practically standard practice and slight modifications may be made in the various shapes of the parts to suit requirements. It is well known 100 by car builders that the surfaces of the plates in proximity to the guides and nearest 110

the centre of the bolster wear very rapidly through coming in frictional contact with the part of the truck (not shown), in which it is adapted to move during the running of the car. As far as we are aware these end plates have been made of malleable iron, or such like tough metal to reduce the wear at this point to a minimum in cars at present in use, but there is still room for improvement in this part of the bolster as it still wears out rapidly, necessitating putting the car out of commission to effect the necessary repair to the badly worn plates. We overcome the above difficulty by making these plate 29 in Figure 3 and plates 32^a in Figures 4 to 10 inclusive, of a hard tempered or spring steel, heat treated to reduce their wear to a minimum. It has been found from actual test and from experiments that bolsters built according to our invention, that is having the surfaces which come in contact with the truck made of spring steel, tend to reduce the wear at this part of the bolster to a minimum and greatly decreases the maintenance cost of cars fitted with same. The spring steel when subjected to frictional contact with the truck tends to polish and forms a first-class bearing surface which reduces the frictional resistance between the truck and the bolster to a minimum and also allows the

car to ride more easily and with less jars than if such surfaces were made of softer metal than spring steel or its equivalent. It is very simple and inexpensive to construct bolster ends with special hard steel bearing plates and greatly reduces the upkeep and necessity of repairs when compared with bolsters of the present type. The bearing plates must be made of a steel of a much harder grade than the surfaces with which they come in contact. 35 40

Having thus described our invention, what we claim is:—

1. In bolster construction, side plates at 45 the ends of the bolster, a plate of channel formation joining the side plates and guides formed integral with the side plates which are made of high carbon steel.
2. In bolster construction, side plates at 50 each end of the bolster, a plate of channel formation joining the ends of the side plates, guide lugs formed in each side plate and means for attaching the side plates to the main body of the bolster, said side plates 55 being made of steel having a high carbon content.

In witness whereof, we have hereunto set our hands.

ERNEST R. VIBERG.
WALLACE C. PARKER.
